COMPACT AND THE LIKE FOR RECEIVING
AND PRESERVING COSMETIC AND SIMI-
LAR PADS

Helen Davies, New York, N. Y.

Application September 26, 1938, Serial No. 231,830

3 Claims. (Cl. 312—31)

This invention relates to compacts, vanity cases, and the like, receiving fabric disks, wafers and the like which are impregnated with skin cleansing, skin treating, skin beautifying, medicinal, therapeutic or other materials, and for substances such as rouge, lip stick and the like.

According to a preferred embodiment of the invention, the container is comprised by two hingedly or otherwise connected sections, one having a compartment or well to contain cleansing disks, wafers or the like with a suitable humidifying arrangement and the other having a compartment, or compartments, to contain powder, rouge, lip stick or other cosmetics or the like. If desired the section containing the elements or substances to be maintained moist, and their moistening means, may be separated from the section containing the cosmetics, or the like, when the case is closed, whereby the cosmetics or the like are not affected by the means for humidifying or maintaining the disks, wafers or the like moist.

In the accompanying drawings, wherein like characters of reference denote corresponding parts in related views:

Figure 1 is a perspective view of a container constructed in accordance with one practical embodiment of the invention, the same being shown open.

Figure 2 is a central longitudinal section through the container as shown in Fig. 1.

Figure 3 is a perspective view showing in separated relationship the moisture containing, well forming pad and its retaining element used in the Fig. 1 embodiment of the invention.

Figure 4 is a perspective view illustrating an alternative embodiment of the invention.

Figure 5 is a cross section through the Fig. 4 embodiment of the invention.

Figure 6 is a view similar to Fig. 4 illustrating another alternative embodiment of the invention; and

Figure 7 is a cross section through the Fig. 6 embodiment of the invention.

Referring to the drawings in detail, first with particular reference to the embodiment of the invention illustrated in Figs. 1 to 3 of the drawings, it will be observed that the container chosen for purposes of illustration in the present instance and designated generally as A, is in the form of a compact or vanity case composed primarily of two sections 10, 10, hinged together as indicated at 11 for relative opening and closing movements and either of which may be con-

sidered as the body of the container and the other as the closure or cover therefor.

The container may be formed from any suitable material and may be of any desired size and shape, and, in accordance with the illustrated embodiment of the invention, one of the sections 10 thereof is divided in any suitable manner into any desired plurality of compartments 12 to contain any desired number of elements or substances such as cosmetics or the like. On the other hand, there is provided to fit within the remaining section 10 a pad 13 of any suitable absorbent and moisture retaining material having formed therein an opening 14 comprising a compartment or well to contain elements or substances such as impregnated facial cleansing disks, wafers or the like, designated as 15, which are required to be maintained moist in order to be maintained in proper condition for use.

Any suitable means may be provided to retain the pad 13 in its related section 10. In this connection and as illustrated in the present instance, the retaining means for the pad 13 comprises a plate 16 of a size and shape to fit within the related section 10 and to be retained therein either frictionally or in any other desired manner. The pad 13 first is placed in its section 10 and then the plate 16 is inserted into said section in overlying relationship to said pad, said plate being snapped, for example, beneath small protuberances 17 extending inwardly from the side walls of the section 10 whereby it is retained in said section and thereby serves to retain the pad 13 therein.

In the plate 16 is an opening 18 which, in the pad retaining position of said plate, alines with the well 14 in the pad, whereby, when the case is opened, access is afforded to said well for the insertion therein and the removal therefrom of the disks, wafers, or other elements 15.

The plate 16, except for the opening 18 therein, may be completely closed and the pad 13 may be moistened by applying water or any other desired liquid thereto at its exposed edge defining the well 14. However, to facilitate quick and easy and thorough moistening of the pad 13, said pad preferably is provided with a plurality of small openings 19 extending therethrough at suitably spaced points and the plate 16 is provided with openings 20 alined with said openings 19. Thus, by dropping water or other liquid through the openings 20 into the openings 19 the entire pad may be thoroughly moistened very easily and quickly. Obviously, when the pad 13 is moistened the moisture contained therein serves to

maintain the disks, wafers or other elements 15 contained in the well 14 moist and in a proper condition for use.

Preferably suitable means is provided to separate the sections 10, 10 from each other when the case A is closed, thereby to prevent the moisture contained in the pad 13 from affecting elements or substances such as cosmetics or the like contained in the compartments 12. A practical means for this purpose may comprise a mirror 21 of a size and shape to fit snugly within the section 10 containing the pad 13 in overlying relationship to the pad retaining plate 16. This mirror 21 may be hinged to the plate 16 as shown, or, alternatively, it may be hinged to the case A. In either case, it is swingable to an open position for most convenient use and to afford access to the well 14, as illustrated in Figs. 1 and 2, and to a closed position in which it serves as a cover for the pad containing section 10 for the purpose stated.

According to the Figures 4 and 5 embodiment of the invention the construction is generally the same as illustrated in Figs. 1 to 3, except that the container, designated generally as A², is of circular shape; the pad 13^a and its retaining plate 16^a according to this form of the invention being in the form of rings.

According to the Figures 6 and 7 embodiment of the invention the well 14^b to contain the disks, wafers or the like 15^b is provided in one of the sections 10^b of the container designated generally as A³, and the pad 13^b for maintaining said disks, wafers or the like moist is contained in the other section 10^b of the case. The well 14^b is formed by a ring-like element 22 permanently or removably mounted in its related section 10^b and the pad 13^b is retained in its section 10^b by a suitably perforated disk-like element 23 which may be frictionally or otherwise suitably retained in said accommodating section 10^b.

As suggested by Fig. 6, the pad retaining plates of the Figs. 1 and 4 embodiments of the invention may be of open-work or screen-like construction to facilitate moistening of the pads.

Obviously, according to each of the forms of the invention, simple, practical means is provided for maintaining the elements or substances 15, such as cleansing disks, wafers or the like in a moist condition best suiting them for use, for in each instance the compartment or well for containing the elements to be maintained moist either is formed directly in an absorbent moisture retaining pad or is in part closed by such a pad when the case is closed. Obviously, too, said

means may readily be embodied in containers such as vanity cases, compacts, or the like of known commercial types or in specially constructed containers of various different designs, 5 and in any instance where the container is designed to contain cosmetics or the like in addition to impregnated disks, wafers or the like, means is provided to prevent the cosmetics or the like from being affected by the moisture utilized for maintaining the impregnated disks, wafers or the like in proper condition for use.

Without further description it is thought that the features and advantages of the invention will be readily apparent to those skilled in the art, 15 and it will of course be understood that changes in the form, proportion and minor details of construction may be resorted to, without departing from the spirit of the invention and scope of the appended claims.

I claim:

1. In a container, an absorbent moisture retaining element disposed in said container and having an opening to contain elements or substances to be maintained moist, a plate overlying said moisture retaining element and engaged with the container to retain said moisture retaining element in said container, said plate having an opening aligned with the opening in said moisture retaining element, and said moisture retaining element and plate having a plurality of aligned openings disposed at spaced intervals around said first mentioned openings to facilitate moistening of said moisture retaining element.
2. In a cosmetic compact container, an absorbent moisture retaining element disposed in said container and having an opening to contain elements or substances to be maintained moist, a plate overlying said moisture retaining element and engaged with the container to retain said moisture retaining element in said container, said plate having an opening aligned with the opening in said moisture retaining element.

3. In a cosmetic compact container, an absorbent moisture retaining element disposed in said container and having an opening to contain elements or substances to be maintained moist, a plate overlying said moisture retaining element and engaged with the container to retain said moisture retaining element in said container, said plate having an opening aligned with the opening in said moisture retaining element and a closure plate fitting snugly in the top of said container in overlying relationship to said first mentioned plate.

HELEN DAVIES.
